Patented Dec. 1, 1970

219,352

HAND-HELD RHYTHMIC DRUM

Paul C. Pierce, 4026 S. State, Salt Lake City, Utah 84107

Filed Nov. 17, 1969, Ser. No. 20,142

Term of patent 14 years

Int. Cl. D17—04

U.S. Cl. D56—1

FIG. 1.

FIG. 2.

FIG. 3.

FIG. 4.

FIG. 5.

FIG. 6.

FIG. 1 is a front, top and side perspective view of a hand-held rhythmic drum, showing my new design;

FIG. 2 is a top plan view;

FIG. 3 is a side elevational view, the opposite side, not shown, being the mirror image thereof;

FIG. 4 is a rear elevational view;

FIG. 5 is a front elevational view; and

FIG. 6 is a bottom plan view thereof.

I claim:

The ornamental design for a hand-held rhythmic drum, substantially as shown and described.
